UNITED STATES PATENT OFFICE.

CHARLES F. HERBOLSHEIMER, OF DENVER, COLORADO.

DOOR ATTACHMENT.

1,240,846.

Specification of Letters Patent. Patented Sept. 25, 1917.

Application filed September 7, 1915. Serial No. 49,188.

To all whom it may concern:

Be it known that I, CHARLES F. HERBOLSHEIMER, a citizen of the United States, and a resident of the city and county of Denver, State of Colorado, have invented certain new and useful Improvements in Door Attachments, of which the following is a full, clear, and exact description, such as will enable others skilled in the art to which the invention appertains to make and use the same, reference being had to the accompanying drawing, forming a part hereof.

My invention relates to attachments for doors for the purpose of preventing flies and other insects from entering the house when the door is opened.

The invention has for its object the provision of a device operable by the opening and closing of the door, whereby the insects are driven away when the door is opened.

Another object of the invention is to provide a device of this character which may be employed as a shade, or awning for the door.

Another object of the invention is to provide a device of this character which may be attached to any door, and which is efficient in operation and effective in purpose.

Another object of the invention is to provide a device of this character which may be attached to the door in such a position that it will not interfere with the opening and closing of the door, or the entrance and exit of persons.

With these and other objects in view, the invention consists of certain novel features of construction, combination and arrangements of parts, as will be fully described with reference to the accompanying drawing.

In this drawing, Figure 1 is an elevation view of a door showing the invention attached thereto; Fig. 2 is an edge view of the door casing, showing the invention applied thereto; Fig. 3 is a plan view of the frame over which the fabric is secured; Fig. 4 is a sectional view, taken on the line 4—4, Fig. 1, showing the device in the dropped position; and Fig. 5 is a sectional view taken on the line 4—4, Fig. 1, showing the device in the raised position.

Corresponding and like parts are referred to in the following description and indicated in all the views of the accompanying drawing by the same reference characters.

Let the numeral 5 represent α the casing

of a door, and the numeral 6 a screen door hinged to said casing, as shown at 7. It will be understood that the door may be hinged at either edge with equal advantage and without changes in the invention. The numeral 7' designates a fan in its entirety. This fan consists of a frame 8, formed of a metal bar 9, bent at its extremities at right angles to form arms 10 and 12. The outer extremities of these arms are curved around a connecting bar 13, as shown at 14. The metal bar 9 is journaled in brackets 15, secured to the door casing 5 above the door 6, whereby the frame 8 will swing in said brackets,

as will be later more fully explained. A member 16 is vertically secured to the upper part of the casing 5, intermediate the brackets 15, and carries a leaf spring 17, which is secured at its upper extremity to said member 16, as shown at 18, the lower extremity

of said leaf spring being free. This leaf spring 17 operates between laterally extended wings 19, whereby the said spring is shielded against becoming entangled in the

fabric of the fan 7'. An operating lever, or finger 20 is fixedly secured to the bar 9, the said finger occupying a position extended downwardly at an angle to the horizontal plane when the door 6 is in the closed position.

Transverse bars 21 and 22 connect the bars 9 and 13, the said transverse bars 21 and 22 being spaced apart, and between which, the finger 20 is arranged, or secured to the bar 9. The top of the door 6 is pro-

vided with a metal protecting strip 23, which engages with the bars 21 and 22 when the door is opened, thereby raising the frame 8 and causing the finger 20 to engage with the spring 17. As soon as this finger has

reached a point past center, the spring 17 acts on the said finger to suddenly throw the frame 8 to its complete elevated position, as represented in Fig. 5, whereby the spring 17 then engages the finger 20, as shown in Fig.

5, to retain the frame 8 in its raised position. A bow-shaped member 24 is curved around the rod 9, on opposite sides of the finger 20, thereby forming a fulcrum of said bow-shaped member 24 on said rod 9. This bow

shaped member 24 forms a loop 25 on one side of the rod 9 and two fingers 26 on the other side of the said rod. Now, when the door is opened and the frame 8 raised, the finger 20 is caused to engage with the loop

25 in front of the latter, while the fingers 26 are moved outwardly, as shown in Fig. 5,

and occupy positions in the path of the door when the latter is being closed. Of course, the door 6 is spring actuated and is moved to its closed position under the influence of the 5 said springs as soon as released. During the closing movement of the door, the wear strip 23 of the door engages with said finger, whereby the bow-shaped member 24 is moved on its fulcrum, and the loop 25 engaging 10 with the finger 20, releases the latter from engagement with the spring 17 and permits the frame 8 to drop by gravity to its lowered position, as represented in Fig. 4. The wear strip 23 is curved over the inner edge of the 15 door, as shown at 27, whereby the door is fully protected from wear incident to engagement of the latter with the fingers 26. A sheet of fabric material 28 is stretched over the frame 8, the said fabric having 20 wings 29 depending from the frame 8 on opposite sides of the door 6.

The operation of the fan 7', during the opening and closing of the door will serve to drive the flies and other insects away and 25 prevent them from entering the room, as will be clearly understood from the construction described.

The fan 7' may also be employed as an awning, and to this end, a rod 30 is pivoted 30 at one extremity to the bar 13, as shown at 31, and at its other extremity to the upper extremity of an operating bar 32, as shown at 33. This operating bar 32 is slidably mounted in brackets 34. Thus, by 35 moving the bar 32 upwardly in said brackets, the fan 7' will be manually raised through the medium of the connecting rod 30, which serves as a support to sustain the fan in its raised position, the bar 32 being 40 locked against moving down by any well known means. Of course, when the fan 7' is employed as an awning, the same will occupy a position intermediate the path of its full swing, and in which position, the 45 fan will slant downwardly, resembling a roof. Also, in such position, the opening and closing of the door will not displace the fan, due to the angle in the fingers 26, as shown at 35, whereby the fingers are permitted 50 to rest on top of the door when the latter is closed and do not form an obstruction to the closing of the door.

While I have described and illustrated

herein, a specific form of my invention, it is understood that the same may be modified 55 and varied without departing from the spirit of the invention, or the scope of the appended claims.

Having thus described my invention, what I claim and desire to secure by Let- 60 ters Patent is:

1. A door attachment, comprising a frame pivoted to the door casing above the door, a spring vertically disposed on said door casing, a finger attached to said frame, said 65 frame adapted to be engaged by the door during the opening movement of the latter for raising said frame, the said finger adapted to be engaged by said spring when the said frame is in its raised position for 70 holding said frame in such position, and a member fulcrumed on said frame and adapted to be engaged during the closing movement of the door for actuating said frame to its down position. 75

2. A door attachment, comprising a frame pivoted to the door casing above the door, a leaf spring secured to said door casing above the door at right angles to the axis of the said frame, a finger secured to said 80 frame, said spring being disposed in the path of said finger, the said frame adapted to be engaged by said door when the latter is opened for raising said frame and causing said finger to engage with said spring, 85 said spring acting on said finger to suddenly throw said frame to its completely raised position and to sustain same in its raised position, a member fulcrumed on said frame and having a part adapted to engage said finger on the rear side thereof and another part adapted to be disposed in the path of the closing movement of the door and engageable by the door while the latter is being closed for releasing said finger from engagement with said spring, and a fabric secured to said frame and having 90 parts depending from the opposite extremities of said frame. 95

In testimony whereof, I affix my signature in the presence of two witnesses.

CHARLES F. HERBOLSHEIMER.
